FIG. 3

FIG. 4.

[HIG]

Fig. 1 is a perspective view taken from the left rear side of a floor scraping machine, showing my new design;

Figs. 2 and 3 are rear and front end views, respectively, thereof;

Fig 4 is a top plan view thereof, and

Fig. 5 is a perspective view taken from the rear right side of Fig. 1.

The handle is shown broken away in part in Fig. 1 and fragmentarily shown in Figs. 2, 4 and 5 for convenience of illustration only.

The dominant features of my design reside in the portions shown in full lines.

I claim:

The ornamental design for a floor scraping machine, substantially as shown and described.
